ALLOY

Jesse O. Betterton, Metuchen, Albert J. Phillips,
Plainfield, and Albert A. Smith, Jr., Metuchen,
N. J., assignors to American Smelting and Re-
fining Company, New York, N. Y., a corpora-
tion of New Jersey

No Drawing. Application May 20, 1937,
Serial No. 143,756

2 Claims. (Cl. 75—167)

This invention relates to lead alloys and pro-
vides certain alloys of calcium, lead and tin
which have been found to possess properties
making them of particular importance in the
5 manufacture of battery grids and sheathing for
electrical conductor cables.

The alloys of the invention consist of 0.01%
to 0.1% calcium, 0.35% to 1.75% tin and the bal-
10 ance lead, it being understood that the alloys,
while essentially ternary compositions, may con-
tain minor impurities within the scope of the in-
vention as defined in the appended claims.

The alloys may be readily compounded in any
15 of several manners, one of the simplest being to
melt the lead in an ordinary cast iron kettle and
stir in the requisite tin and calcium, the latter
being added in the form of a calcium-lead alloy.

The advantages accompanying the use of the
20 alloys of the invention in the manufacture of
such products as battery grids and cable sheath-
ing are readily apparent from a consideration of
the properties of the new alloys.

Thus, the alloys of the invention are eminently
25 more stable upon remelting than are the calcium-
lead alloys recently advocated for battery grids
as a substitute for antimonial grid metal. This is
well illustrated from the following tabulated re-
30 sults of drossing tests conducted on several of
the new alloys by melting 1000 grams of the
alloy in a special machine equipped with a re-
volving paddle which swept the surface of the
molten metal (350° C.—360° C.) at exactly 100
35 R. P. M. for 30 minutes after which the remain-
ing metal was skimmed clean, cast and chemi-
cally analyzed. A typical result from a like test
on a binary calcium-lead alloy is included for
the purpose of comparison.

40	Alloy composition before dross test	Alloy composition after dross test	Per cent Ca re- tained
	Pb, 0.065% Ca.	Pb, 0.010% Ca.	15
	Pb, 0.062% Ca, 0.46% Sn.	Pb, 0.038% Ca, 0.46% Sn.	58
	Pb, 0.058% Ca, 0.95% Sn.	Pb, 0.035% Ca, 0.95% Sn.	60
45	Pb, 0.037% Ca, 1.20% Sn.	Pb, 0.029% Ca, 1.14% Sn.	78

The ability of the calcium-lead-tin alloys of
the invention to retain a much larger percentage
of their calcium upon remelting than is the case
50 when remelting binary calcium-lead alloys is of
considerable importance when one considers the
large amounts of metal that must be remelted
in many processes as, for example, in manufac-
turing battery grids where the weight of metal
55 to be remelted and returned to the process often
approximates the weight of satisfactory grids
produced. Hence, it will be appreciated that
while calcium-lead alloy grids may be considered
to constitute an improvement over antimonial
55 grids in that they are said not to accelerate

sulphation or cause self-discharge of the battery,
the calcium-lead-tin alloys of the invention are
a decided improvement over the calcium-lead
5 grids in that they are vastly more stable upon
remelting and in this respect more closely ap-
proach antimonial grid metal which may be re-
peatedly remelted with very little change in
chemical composition.

In addition to the marked increase in stability
of the calcium-lead-tin alloys of the invention
over alloys of calcium-lead, the presence of the
tin has been found to impart increased tensile
10 strength. Thus a cast alloy consisting of 0.054%
calcium, 1% tin and the balance lead exhibited
a tensile strength of approximately 8000 lbs./sq.
in. as compared to 5500 lbs./sq. in. for a cast
alloy consisting of 0.057% calcium and the bal-
15 ance lead. Apparently, the tin exerts a strength-
ening effect by stiffening the matrix. On ex-
truded material, tensile strength values of about
6500 lbs./sq. in. were obtained for the calcium-
lead-tin alloy but because of the technique em-
ployed in the tests this figure should not be con-
sidered as representing the maximum obtainable.
Fatigue strength was found to be approximately
20 1700 lbs./sq. in. for 20 million cycles at 2000
R. P. M.

It will thus be apparent to those skilled in the
art that the characteristics of the improved alloys
fit them for such special uses as cable sheathing
25 and battery grids. In connection with the latter
use it may be pointed out that the new alloys
retain their hardness upon remelting and lend
themselves to grid manufacture by punching or
stamping methods which some manufacturers
30 have long felt to be desirable but to which anti-
monial lead is not easily adapted by reason of
the fact that while it can be rolled into sheet
material, the sheets are softer and less rigid than
the cast metal and the normally rolled sheet
35 actually softens with time unless the tendency
be overcome by heat treatment thereby making
the process commercially unattractive.

While the beneficial properties which charac-
terize the improved alloys of the invention are
exhibited, to a more or less degree, by any com-
position falling within the limits hereinbefore
specified (0.01% to 0.1% Ca, 0.35% to 1.75% Sn,
balance Pb), it has been found that a tin range
of between 0.5% and 1.25% is preferable for most
50 uses.

What is claimed is:

1. An alloy consisting of 0.01% to 0.1% cal-
cium, 0.35% to 1.75% tin, and the balance lead.
2. An alloy consisting of 0.01% to 0.1% cal-
cium, 0.5% to 1.25% tin, and the balance lead.

JESSE O. BETTERTON.

ALBERT J. PHILLIPS.

ALBERT A. SMITH, JR.
